UNITED STATES PATENT OFFICE.

JAMES F. CRAVEN, OF PITTSBURGH, PENNSYLVANIA, ASSIGNOR TO CRAVEN ENGINEERING COMPANY, OF PITTSBURGH, PENNSYLVANIA, A CORPORATION OF PENNSYLVANIA.

RECEPTACLE WITH METAL LABEL.

1,077,259.

Specification of Letters Patent.

Patented Nov. 4, 1913.

Application filed February 14, 1912. Serial No. 677,529.

To all whom it may concern:

Be it known that I, JAMES F. CRAVEN, a resident of Pittsburgh, in the county of Allegheny and State of Pennsylvania, have invented a new and useful Improvement in Receptacles with Metal Labels, of which the following is a specification.

This invention relates to cans or other containers for various substances, and more particularly to cans or containers for food stuffs, greases, oils, or greasy and oily substances.

The object of the invention is to provide a container for the purpose stated which is of cheap construction, is strong, and which will not become soiled or discolored by the contents, and which will effectively hold greases and oils, or substances of a greasy and oily nature.

20 The invention comprises the construction and arrangement of parts hereinafter described and claimed.

In the accompanying drawings Figure 1 is a vertical section through one form of a 25 container embodying the invention; Fig. 2 is an elevation of the same; Fig. 3 is a horizontal section through the same; Fig. 4 is a fragmentary sectional view of a portion of Fig. 1 showing the parts on an enlarged 30 scale; Fig. 5 is a similar view showing a modification; Fig. 6 is a vertical section through the upper portion of a container showing still another modification; Fig. 7 is a view similar to Fig. 4 showing still 35 another modification; and Figs. 8 and 9 are cross sectional views through other forms of containers.

Lubricating greases, butter, lard, peanut butter and other substances of a similar 40 nature containing oil are usually put up in tin sheet metal cans of various sizes. These when manufactured of sheet metal of the requisite strength are quite costly. Cheaper substances, such as paper, have heretofore 45 not been satisfactory for containers for such substances because the oil of the grease or other substance penetrates the paper, and in time causes the paper to fail, but in any event, so discolors the exterior 50 that it is unsightly. Paper or other fiber can be treated to prevent the oil of greases or similar substances from penetrating the same. It has been proposed to use treated paper tubes for this purpose with sheet

metal heads crimped onto the same. With 55 such containers it is necessary for commercial reasons to use an exterior label, to show the contents and the trade mark, directions, and so on, and to give a good external appearance such label must extend 60 for the full length of the can and is preferably crimped or beaded in one with the sheet metal head. Such labels must be either of glazed paper or varnished so as not to readily soil, and some care must be 65 also exercised in putting them onto the tube or similar container, so that the cost for such labels for applying them to the containers is a very considerable item. It has been found that the oily and greasy 70 substances in such containers will escape over either end of the paper bodies and work in between the label and the body where the label is pasted, crimped or beaded under the sheet metal head, and work its 75 way up or down between the label and the body by capillary action, discoloring the label so that it is unsightly.

The present invention is designed primarily to overcome the above difficulties for 80 containers for putting up greases and other substances containing greasy or oily constituents. It is, however, not limited to this use.

Primarily the invention consists in providing a paper tube or other container with 85 an external sheathing of very thin sheet metal which also constitutes the label.

Various forms of the invention are illustrated in the drawings.

As shown in Fig. 1 the container comprises a paper body 1 in the form of an ordinary paper tube. The bottom of the body is closed by means of a sheet metal cap 2 and the top by means of a sheet metal cap 3, and provided with a nozzle 4 forming a discharge outlet, said nozzle being provided with a suitable closure, as is usual. The body of the container is surrounded by means of a metal sheathing or label 6, 100 which will be formed of a very thin sheet metal, the finest form of sheet iron or steel which can be practically procured. The edges of the sheathing are united by a seamed or interlocked joint 7 familiar to 105 can makers, and said tubular sheathing is of such size that it will smoothly slip over the paper body. This sheathing is slipped

upon the paper body before the heads or caps are applied and is preferably very slightly flared at its ends before being applied to the paper body. Preferably, the 5 heads or caps are formed with a centrally depressed portion 30 which extends within the paper body when the cap is applied, and has an annular wall snugly fitting the interior thereof. The perimeter of each head 10 or cap is beaded or crimped around the end of the body and the flared sheath, as at 8, and is bent inwardly by any suitable tool or machine to indent the metal of the sheath and force it and the perimeter of the cap 15 into the paper body, as at 19. This not only secures the heads or caps to the paper body but also secures in place the metal sheath 6, both body and sheath being tightly squeezed or pressed between de- 20 pressed portion 30 of the head or cap and its perimeter. The consequence is that even if grease or the oil from greases or oily substances works in between the sheet metal caps and the ends of the paper 25 body and between the sheathing 6 and said body, it can do no harm as it can in no event penetrate to the exterior. The sheet metal sheathing can have the label applied thereto in any suitable way, such as stencil- 30 ing the same thereon, but preferably by lithographing process, which gives admirable results on sheet metal, making a very ornamental finish. The lithographing process also has the effect of rendering the 35 metal rust proof, so that where the container is to be used for putting up substances which contain no water or other corrosive substance, the sheathing can be made from ordinary black plate, which is 40 cheaper than tin plate, and which gives even better results in the lithographing process than tin plate. Where the contents of the 45 can contain water or other corroding substance, the sheathing must be formed of plate which is tinned or otherwise treated, at least on its inner surface.

The lithographing of the label and trade mark, indicated at 10, on the metal envelop, is a cheap process, and when completed the 50 container is provided with a sheet metal label so to speak. These complete sheet metal labels cost somewhat more than paper labels which are glazed or varnished. The cost of applying same to the container is, 55 however, much less, as it involves much less labor, consisting in forming the sheet metal in a sealed tube, slipping of this over the metal container and securing it in place by beading the caps on the container, all of 60 which are machine operations and less costly than the application of a paper label to the container, besides saving the cost of glue or adhesive necessary with the paper labels. Furthermore, the sheet metal envelop or 65 label possesses a considerable amount of

strength so that the paper body can be thinner than where paper labels are used, thereby effecting a considerable saving in the paper stock. It will of course be understood, however, that the paper body is always made of such thickness and strength as to be self-sustaining and capable of supporting and holding the contents of the container by itself, the metal sheath or label not being depended upon for this purpose. 70 The result is that the container is even less costly than a paper container with a good grade of paper label thereon and is very materially cheaper than containers made solely of sheet metal of the requisite 75 strength. The container also is more slightly, less liable to soil, and can be easily wiped off in case it does become soiled.

In the drawings the invention has been shown applied specifically to what are 80 known as grease guns, or containers for containing greasy, pasty and other semi-solid substances, such as lubricating greases, vaseline, and numerous other substances of a similar nature, and provided with means 85 for forcing the contents out of the container. The means illustrated comprises a piston or follower 12 provided with a cup leather or similar device 13 and arranged to be moved endwise in the container by means of a band, 90 tape, cord or wire 14 secured to said piston or follower and to a winding shaft 15 mounted in the nozzle 4, said winding shaft being provided with a turning handle 16. The form of winding shaft and connection 95 of the tape or band 14 therewith is similar to that illustrated in my application Serial No. 674,039 filed January 29, 1912. It need not be described herein, as any means for moving the piston or follower longitudinally 100 in the tube or container is within the scope of the present invention.

The container described is particularly advantageous where a piston or follower is used. In case the container is formed solely 110 of sheet metal any slight indentation giving a permanent set to the metal will be sufficient to arrest longitudinal movement of the piston or follower and prevent the extrusion of the contents. The paper tube, however, 115 has a considerable amount of elasticity and even if subjected to a force sufficient to permanently indent a sheet metal container will spring outwardly and regain its original circular shape so that longitudinal movement of the piston or follower is not prevented by ordinary blows to which the container is subjected.

The sheathing can be made of any kind of metal and in use will be made of the 125 cheapest metal available as it does not require any considerable strength, or, for that matter, finish. Ordinary black iron or steel plate of 34 gage or thinner answers the purpose. The thinner it is the better it is 130

from the point of view of cost. The lithographing of the label thereon gives the necessary finish. For certain purposes above stated the metal will probably be tinned or otherwise coated.

Fig. 5 illustrates a modification in which the caps or heads instead of being beaded on as is usual, are crimped on, as indicated at 20. This joint, however, secures together the caps or heads, and the body and sheath in the same manner as the form in Fig. 4, both the perimeter of the cap or head and the metal label being indented into the paper body, as shown.

Fig. 6 shows still another modification in which the ends of the sheathing are provided with flanges 21 and the edges of the heads are folded together or interlocked with said flange.

Fig. 7 shows still another modification in which the paper head 23 and the ends of the body are crimped or rolled directly together, as at 27, and the sheathing 6 is turned over said crimped portion as at 28.

Fig. 8 shows still another modification wherein the heads of the container are formed from paper disks 23 flanged as at 24 to fit within the ends of the tubular body 1. The sheathing 6 in this case is made somewhat longer than the body and the ends are merely crimped or turned over the edges of the body of flange 24, as shown at 25. The nozzle 4^a in this case is crimped into the paper head, as shown at 26.

In Fig. 9 is shown an ordinary shaped can or container in which the end cap 3 is flat and turned or crimped into the sheath 6 and paper tube 1. A wide flat closure 29 is screwed over the discharge nozzle. No means for forcing the substance out of the receptacle is shown either in this form of the invention or in that of Fig. 8, and it is to be understood that such means are not essential.

Various other arrangements of these parts will readily suggest themselves.

The container described can be used for a great variety of purposes.

I am aware that sheet metal sheathings

have been applied to wooden boxes and like receptacles. I am also aware that labels have been lithographed onto sheet metal containers. I believe myself, however, to be the first to provide a container having a paper body and a very thin sheet metal sheathing thereon which forms the label and whose purpose primarily is to replace the usual paper labels with the resultant disadvantages of the latter, and incidentally to strengthen the paper body, enable a thinner paper body to be used, and enable the use of a body formed of untreated paper for all kinds of substances, even those which ordinarily cannot be placed in untreated paper containers.

What I claim is:

1. A receptacle for holding greasy or oily substances, comprising a self-sustaining paper tube forming the receptacle body, a thin tubular metal sheath surrounding said paper body, end caps or heads forming closures for the ends of said tubes and having their peripheral portions incorporated in a joint with the ends of both the paper body and the metal sheath, and thereby permanently and non-removably securing both the end caps or heads and the sheath to the paper body.

2. A receptacle for holding greasy or oily substances, comprising a self-sustaining paper tube forming the receptacle body, a thin tubular metal sheath surrounding said paper body, and sheet metal caps or heads having their central portions depressed, and fitting within the ends of the paper body and having their peripheral portions crimped around the ends thereof, the end portions of both the paper body and sheath being compressed between the central depressed portions and the peripheral portions of said end caps or heads.

In testimony whereof, I have hereunto set my hand.

JAMES F. CRAVEN.
